UNITED STATES PATENT OFFICE

2,115,692

PRINTING APPARATUS

Robert J. Thorn, Chicago, Ill., assignor to Reynolds Appliances Corporation, Chicago, Ill., a corporation of Illinois

Application April 8, 1937, Serial No. 135,658

23 Claims. (Cl. 197—2)

The present invention relates generally to printing apparatus. More particularly the invention relates to that type of printing apparatus which is designed primarily to print cards for sign or placard forming purposes and comprises (1) a rectangular card supporting base; (2) a supporting structure over the base; (3) a type case which is supported on the structure for universal movement in a horizontal plane over the base and has a set of vertically movable type therein with springs for urging the type upwards into an inoperative position within the case; (4) a vertically slideable plunger which is disposed over the type case and is adapted when the type case is shifted so that a type is disposed directly therebeneath to be lowered so as to shift the type downwards and cause it to effect an impression on the card; (5) a card retaining bar which extends transversely across the front portion of the top of the base and is retained by a guide member so that it is longitudinally shiftable for card feeding purposes; and (6) mechanism which is operated conjointly with the type projecting plunger and serves automatically to shift the card receiving bar for card feeding purposes at the conclusion of each printing operation.

One object of the invention is to provide a printing apparatus of this type which is an improvement upon and may be operated more readily than previously designed apparatus of the same general character.

Another object of the invention is to provide a printing apparatus of the type under consideration in which the supporting structure for the type case is in the form of a hollow arm over the rear portion of the base and a U-shaped carriage which supports the type case for sliding movement to and from the front of the base and is suspended from the front end of the hollow arm so that it together with the type case is shiftable sidewise.

Another object of the invention is to provide a printing apparatus of the aforementioned type and character in which the mechanism for automatically feeding the card retaining bar at the conclusion of a printing operation is of novel design and not only operative in a positive and efficient manner but also includes a lost motion connection whereby feed of the card retaining bar is avoided or precluded when the type projecting plunger is raised to a slight extent in order properly to align a type therebeneath.

A further object of the invention is to provide a printing apparatus of the type hereinbefore referred to in which the vertically movable type

are mounted in a novel manner within the case.

A still further object of the invention is to provide a sign or placard printing apparatus which occupies but a small amount of room and may be produced at a comparatively low and reasonable cost.

Other objects of the invention and the various advantages and characteristics of the present printing apparatus will be apparent from a consideration of the following detailed description.

The invention consists in the several novel features which are hereinafter set forth and are more particularly defined by claims at the conclusion hereof.

In the drawings which accompany and form a part of this specification or disclosure and in which like numerals of reference denote corresponding parts throughout the several views:

Figure 1 is a perspective of a printing apparatus embodying the invention;

Figure 2 is a fragmentary perspective showing the latch which is associated with the carriage and serves to hold the carriage and type case against sidewise shift when the apparatus is not in use;

Figures 3 and 3^a are fragmentary perspectives showing the arrangement and design of the gauge for showing the operator of the apparatus the line on which impressions will be made on the card in response to reciprocation or vertical movement of the type projecting plunger;

Figure 4 is a vertical longitudinal sectional view of the apparatus showing in detail the manner in which the type case is supported by the carriage for sliding movement to and from the front of the base and also the manner in which the carriage is suspended from the front end of the hollow arm so that it together with the type case is shiftable sidewise;

Figure 5 is a reduced vertical transverse sectional view taken on the line 5—5 of Figure 4 and illustrating in detail certain parts of the mechanism for automatically shifting or feeding the card retaining bar at the conclusion of each printing operation;

Figure 6 is a vertical transverse sectional view taken through the central portion of the base and showing the cross-sectional design of the base as well as the type case and the hollow arm from which the type case supporting carriage is suspended;

Figure 7 is a perspective of a type;

Figures 8 and 9 are top and bottom views respectively of the type of Figure 7;

Figure 10 is a perspective of one of the washers at the upper end of the type;

Figure 11 is a fragmentary perspective of the upper end of the shank portion of a type;

Figure 12 is an enlarged vertical sectional view taken on the line 12-12 of Figure 6 and illustrating the manner in which the plunger enters the type case for type projecting purposes;

Figure 13 is an enlarged vertical sectional view taken on the line 13-13 of Figure 6 and illustrating in detail the control member which forms part of the automatic feed means for the card retaining bar and is located alongside of and vertically shiftable with the type projecting plunger;

Figure 14 is a plan view of the front portion of the base of the apparatus showing in detail the construction of the card retaining bar and the manner in which it is slidably connected to the guide member;

Figure 15 is an enlarged vertical transverse sectional view taken on the line 15-15 of Figure 14 and showing the one way clutch which is slidably mounted on the card retaining bar and constitutes another one of the operating parts of the automatic feed mechanism;

Figure 16 is a vertical transverse sectional view on the line 16-16 of Figure 15;

Figure 17 is a detail sectional view taken on the line 17-17 of Figure 14 and illustrating the construction and design of the device for braking or retarding sliding action of the card retaining bar relatively to the guide member;

Figure 18 is a plan view of the brake device which is shown in Figure 17;

Figure 19 is a perspective of the housing part of the one way clutch; and

Figure 20 is a perspective of the dog or movable part of the clutch.

The printing apparatus which is shown in the drawings constitutes the preferred embodiment of the invention. It is designed or adapted primarily to print cards in order to form signs or placards and comprises as the main parts thereof a card supporting base 21, a hollow supporting arm 22, a carriage 23, a type case 24, a manually operated type projecting plunger 25, and a card retaining bar 26. In addition to these parts the apparatus comprises mechanism for moving the card retaining bar 26 to and from the front of the base 21 in order longitudinally to move or adjust the card for line spacing purposes and also mechanism for automatically shifting the bar 26 longitudinally after each printing operation for card feeding purposes.

The base 21 serves as a support for the card to be printed. It is rectangular, as shown in the drawings and comprises a top 27, a front 28, a back 29 and a pair of sides 30. The top 27 is flat and is adapted to have the card to be printed rest flatly thereon. The front and back 28 of the base depend from and are formed integrally with the front and bottom margins of the top 27 respectively and together with the sides 30 support the top 27 in an elevated position with respect to the table or supporting structure upon which the apparatus is set or mounted. The sides 30 of the base depend from and are formed integrally with the side margins of the top 27 and are suitably joined at the ends thereof to the end margins of the front and back. The central portion of the top 27 of the base is provided with a substantially square cut-out 31 in which is disposed a flat piece 32 of rubber or like material. This piece forms a platen against

which the printing is done. It is disposed directly beneath the type projecting plunger 25 and is arranged or positioned so that the top face thereof is flush with the top face of the top 27 of the base. The central portion of the top 27 is reinforced against sagging by means of a channel type member 33. The latter, as shown in Figures 4 and 6 of the drawings, extends between the front and back of the base 21 and embodies out-turned flanges 34 along the top edges 10 of the sides thereof. These flanges fit against and are welded or otherwise suitably secured to the bottom face of the top 27 of the base.

The hollow supporting arm 22 overhangs the rear portion of the base 21 and is supported at its rear end by means of a pair of legs 35. It is positioned midway between and in parallel relation with the sides 30 of the base, extends forwardly from the back 29 of the base to a point slightly forwards of the platen forming piece 32 and comprises a pair of sides 36, a top 37, a front plate 38, and a back plate 39. The sides of the arm are held in laterally spaced relation by the top 37 and define with the top and the front and back plates an elongated compartment 40. The front plate 38 embodies an inturned marginal flange 41 and serves as a removable closure for this compartment. The flange 41 extends in lapped relation with the front margins of the sides 36 and the top 37 of the arm and is removably secured in place by means of screws 42. When these screws are loosened the front plate 38 may be removed in order to provide access to the front end of the compartment 40. The back plate 39 extends across the rear margins of the sides and top of the arm and forms a rear closure for the compartment 40. The legs 35 are formed integrally with the rear portions of the bottom margins of the sides 36 of the arm and are downwardly divergent. They space the arm above the base a sufficient distance to accommodate the carriage 23 therebeneath and embody outwardly extending flanges 43 along the bottom margins thereof. These flanges fit against the top face of the top 27 of the base and are secured in place by means of screws 44. The back plate 39 of the arm embodies a bottom extension 45 which extends between and is suitably secured to the rear margins of the legs 35 and closes the rear portion of the space between the legs.

The carriage 23 together with the arm 22 serves as a supporting medium for the type case 24. It underlies the front and central portions of the arm 22 and comprises a pair of laterally spaced side pieces 46, a back piece 47, a top piece 48, and a bottom piece 49. The side pieces of the carriage are formed integrally with and project forwardly from the side margins of the back piece 47 and together with said back piece form a U-shaped pocket for the type case 24. The top piece 48 extends across the central portions of the top margins of the side pieces and is spaced from the back piece 47 and the front ends of the side pieces 46. It embodies an upturned flange 50 along the front margin thereof and has down-turned ends 51 which fit against the inner faces of the side pieces 46 and are riveted or otherwise fixedly secured in place. The bottom piece 49 extends between the rear portions of the bottom margins of the side pieces 46 and has an upturned flange 52 along the rear margin thereof and upturned end flanges 53. The flange 52 abuts and is suitably secured to the bottom margin of the back piece 47 and the

upturned end flanges 53 fit against and are riveted or otherwise fixedly secured to the inner faces of the side pieces 46 of the carriage. The front margin of the bottom piece 49 terminates adjacent to the central portions of the bottom margins of the side pieces 46. The front ends of the sides 46 are reinforced against inward or outward bending by means of an angle bar 54. This bar has upturned ends which fit against and are riveted to the inner faces of the side pieces 46. The carriage 23 is suspended from the hollow supporting arm 22 so that it together with the type case 24 is shiftable sidewise over the base 21. The means for suspending the carriage so that it is shiftable in this manner comprises a horizontally disposed angle bar runner 55 at the back of the carriage and a horizontal runner 56 and a horizontal track 57 at the front of the carriage. The runner 55 comprises a vertical leg 58 and a horizontal leg 59 and extends across the upper margin of the back piece 47 of the carriage 23. The vertical leg 58 is welded or otherwise fixedly secured to the rear face of the back piece 47 and the horizontal leg 59 projects rearwardly from the top margin of the vertical leg and rides on a pair of rollers 60. The latter are located slightly outwards of the sides 36 of the hollow supporting arm 22 and are mounted on horizontal spindles 61 which are carried by a pair of brackets 62. The latter, as shown in Figures 1 and 4, fit against and are secured to the sides 36 of the arm 22. In order to prevent sidewise tilting of the carriage and the type case the bracket 62 is provided with a pair of rollers 63. The latter overlie the rollers 60 and bear against the top face of the horizontal leg 59 of the angle bar runner 55. The runner 55 and the roller 60 constitute a slide suspension means for the rear portion of the carriage. The runner 56 extends across and is fixedly secured to the front face of the upturned flange 50 of the top piece 48 of the carriage. The ends of the runner project beyond the side pieces 46 of the carriage and the upper margin of the runner extends upwards and then downwards, as shown in Figures 1, 4, 12, and 13, and forms an inverted V-shaped channel 64. The ends of the runner 56 are reinforced against bending by way of a pair of triangular brackets 65. These brackets (see Figure 1) are secured to and project outwardly from the front ends of the side pieces 46 of the carriage. The horizontal track 57 underlies the front end of the hollow supporting arm 22 and is secured in place by way of a pair of brackets 66. The latter, as shown in Figures 1 and 6, are riveted against the outer faces of the sides 36 of the arm. The track is substantially the same in length as the horizontal runner 56 and the lower margin thereof underlies the upper margin of the runner 56 and extends forwards and then upwards so as to define a V-shaped channel 67 directly beneath the channel 64. Balls 68 fit within the two channels and form a roller connection whereby the runner 56 together with the carriage and type case is permitted to slide longitudinally with respect to the track 57. The runner 56 and the track 57 together with the balls 68 form a slide type suspension means for the front portion of the carriage 23. The extremities of the upper margin of the runner 56 are bent inwards to form stops 69 which coact with stops 70 at the ends of the track 57 to prevent the balls 68 from rolling from the ends of the channels 64 and 67. In order to assist the rollers 63 in preventing tilting of

the carriage 23 and the type case 24 rollers 71 are provided. These rollers are two in number and underlie the track 57. They are mounted on horizontal spindles on the runner 56 and bear against the channel forming portion of the track. In view of the runner and roller slide type suspension means at the rear portion of the carriage and the runner and track slide type suspension means at the front of the carriage, the carriage together with the type case is permitted to slide laterally in a rectilinear manner over the base 21 of the apparatus. Sidewise shift or sliding movement of the carriage is limited by means of a pair of stop forming brackets 72. These brackets are secured to the top face of the top piece 48 of the carriage and coact with the sides 36 of the hollow supporting arm 22. One of the brackets operates to limit sidewise shift of the carriage in one direction and the other bracket operates to limit sidewise shift of the carriage in the opposite direction.

The type case 24 carries, as hereinafter described, a set or plurality of vertically movable type 73 and is mounted between the side pieces 46 of the carriage 23 so that it is shiftable horizontally backwards and forwards. It comprises a pair of sides 74, a front 75, a back 76, a combined type selecting and positioning top plate 77, a bottom plate 78 and a partition 79, and is adapted because of the sliding connections between it and the carriage and the slide type suspension means between the carriage and the hollow supporting arm 22 to be moved universally in a horizontal plane over the base in order to bring any desired type under the type projecting plunger 25 for type projecting and impression forming purposes. The sides are disposed slightly inwards of the side pieces 46 of the carriage 23 and form with the front 75 and the back 76 a type compartment 80. The combined type 40 selecting and positioning top plate 77 closes the top of this compartment and is suitably secured in place so that the top face thereof is substantially flush with the top edges of the sides and the front and back of the case. The bottom 45 plate serves as a closure for the bottom of the type compartment 80 and is fixedly secured to a frame-like ledge 81 within the bottom margins of the sides 74 and the front and back of the case. The partition 79 extends horizontally 50 across and divides in two the type compartment 80 and rests on and is fixed to a frame-like ledge 82 which fits against and is secured to the central portions of the inner faces of the case sides, front and back. The sliding connections whereby the type case is supported so that it is shiftable backwards and forwards for type positioning purposes comprise a pair of angle bar tracks 83 and rollers 84. The tracks, as shown in Figures 4 and 6, fit against and extend lengthwise 60 of the side pieces 46 of the carriage 23 and embody vertical legs 85 and horizontal legs 86. The vertical legs are welded or otherwise fixedly secured against the inner faces of the side pieces 46 and the horizontal legs are formed integrally 65 with and project outwardly from the bottom margins of the vertical legs. The rollers 84 ride on the horizontal flanges 86 of the tracks 83 and are carried by journal box type blocks 87 which are secured to the outer faces of the sides 74 70 of the type case 24. The rollers are preferably four in number and are arranged so that there are two at the back of the case and two at the case front. Tilting of the type case is prevented by way of a set of four rollers 88. These roll- 75

ers are disposed beneath the rollers 84. They bear against the bottom faces of the horizontal legs 86 of the angle bar tracks 83 and are carried by spindle equipped blocks 89 which fit against 5 and are secured to the lower corner portions of the outer faces of the sides 74 of the type case. Forward and backward shift of the type case and lateral shift of the type case and carriage are effected by way of a U-shaped handle 90. This 10 handle is located in front of the type case and embodies outturned ears 91 which fit against and are secured to the front 75 of the case. By grasping the handle 90 and shifting it forwards or rearwards or laterally the type case may be 15 moved universally in a horizontal plane and any desired type within the case may be brought into registry with the plunger 25. The type 13 are disposed in row form within the compartment 80 in the type case 24 and comprise enlarged 20 heads 92 and vertically extending shanks 93. The shanks, as shown in Figure 7, are square in cross-section and extend through and are vertically slidable in aligned square holes 94 in the bottom plate 78 and the partition 79. The enlarged heads 92 are fixedly secured to the lower 25 ends of the shanks 93 and have on the bottom faces thereof type characters 95. They are adapted, as hereinafter described, to be individually projected in a downward direction towards 30 the platen forming piece 32 by the plunger 25 and when in their retracted or inoperative position bear or abut against the bottom face of the bottom plate 78 of the type case. The shanks 93 are of such length that when the type are in 35 their retracted positions the upper ends thereof terminate directly beneath the combined type selecting and positioning plate 71. Compression springs 96 surround the upper ends of the type shanks 93 and serve to urge the type upwards 40 into their inoperative position. The lower ends of the springs bear against the partition 79 in the type compartment 80 and the upper ends of the springs abut against washers 97 on the upper ends of the type shanks. As shown in Figures 7, 8, and 10 the washers 97 have square 45 apertures 98 therein and fit within grooves 99 in the upper ends of the type shanks. The apertures 98 are the same in area as the cross-sectional area of the type shanks. In assembling 50 the type the shanks 93 are inserted through the aligned square holes 94 in the bottom plate 78 and the partition 79 of the type case and are then slid upwards until arrested as the result of abutment or engagement of the enlarged heads 55 92 with the bottom plate 78. After this step or operation the compression springs 96 are mounted on the upper ends of the shanks of the type and slid downwards until the lower ends thereof abut against the partition 79. Thereafter the 60 washers 97 are placed on the upper ends of the type shanks 93 and are slid downwards until they register with the grooves 99. After such sliding movement the washers are rotated approximately 45° relatively to the shanks 93 in 65 order to bring the apertures 98 out of registry with the sides of the shanks and effect interlocking connections between the washers and the grooves. After rotating the washers in this manner the upper extremities of the springs are inserted through the apertures 98, as shown in Figure 7, in order to hold the washers against rotation relatively to the shanks of the type. In 70 order to permit downward projection of the type by the plunger 25 the top plate 77 of the type case is provided with a set of square holes 100.

These holes are disposed in registry with the upper ends of the shanks 93 of the type and permit the plunger to be shifted downwards into the type compartment 80 for type projecting purposes. As shown in Figure 1 the holes 100 5 are designated by means of characters 101. The latter are in the form of letters and numbers and correspond with the type characters 95 on the enlarged heads 92 of the type so that the operator of the apparatus may readily determine the character of the type which is associated with each hole 100. Preferably there are upper and lower case type within the type case as well as suitable numbers for printing signs in order that any desired word or combination 10 of figures may be impressed upon the sign forming card. The type characters 95 on the enlarged heads 92 of the type are inked by means of a pair of inking rolls 102. These rolls, as shown in Figures 4 and 12, extend horizontally 15 between the side pieces 46 of the carriage 23. They are disposed in the space between the angle bar 54 and the front margin or edge of the bottom piece 53 of the carriage and are yieldingly or resiliently supported by means of spring 20 arms 103. The latter are fixed to brackets 104 on the inner faces of the side pieces of the carriage and have U-shaped bearing forming distal ends 105 for trunnions 106 at the ends of the rolls. As shown in Figures 12 and 13 the arms 30 103 are so arranged that they hold the upper periphery of the rolls in a slightly elevated position with respect to the type characters 95 on the enlarged heads 92 of the type. When the type case 24 is shifted rearwards it passes over 35 and urges downwardly the rolls 102 and the type characters 95 come in contact with and are inked by the peripheries of the rolls. Because of the arrangement of the inking rolls inking of the type characters 95 of the type is effected after the 40 type case is shifted rearwards with respect to the carriage 23. By reason of the fact that the distal ends of the spring arms 103 are U-shaped the inking rolls 102 may be readily removed from the arms for replacement or inking purposes. 45 In view of the fact that the rolls are disposed beneath the type case and within the U-shaped pocket which is formed by the carriage 23 there is little if any likelihood of anything being accidentally brought into contact with the rolls. 50 The type projecting plunger 25 extends vertically through the front end of the hollow supporting arm 22 and is confined to vertical sliding movement by way of a pair of vertically spaced plates 107 and 108. These two plates are carried 55 by a band type bracket 109 on the front end of the arm 22. As shown in Figures 4, 6, 12, and 13 this bracket 109 embodies a bottom part 110, a pair of side parts 111 and a top part 112. The side parts extend inwardly and upwardly, as 60 shown in Figure 6, and are fixedly secured to the sides 36 of the arm 22 by way of screws. The bottom part 110 is positioned so that it is substantially flush with the bottom edges of the sides 36 and carries the plate 108 so that the front portion of the latter projects forwardly of the bracket 109 and terminates slightly inwards of the front plate 38 of the arm 22. The top part 112 of the bracket 111 is spaced a slight distance 65 from the top 37 of the arm and carries the plate 107 so that its forward or front portion overlies the front portion of the plate 108. The plunger 25 is square in cross section and extends through and fits slidably in vertically aligned square holes 70 113 in the plates 107 and 108. The lower end of 75

the plunger projects beneath the arm 22 and embodies a tapered extremity 114 which is adapted when the type case is positioned so that one of the holes 100 in the top plate 17 is disposed directly beneath the plunger to enter said hole in response to downward movement of the plunger and to project downwards the type beneath said hole and cause the type character on the enlarged head of the type to engage the card and make an impression thereon. By reason of the fact that the extremity 114 is tapered the plunger when shifted downwards in order to project the type from the case for printing purposes will readily enter the subjacent hole 100 and if such hole is not in true registry with the plunger will automatically cause the type case to move so as to effect proper registry of such subjacent hole. The upper end of the plunger 25 extends upwards through a hole 115 in the front portion of the top 37 of the hollow supporting arm 22. The plunger is vertically reciprocated by means of a crank 116. This crank is located adjacent to one of the sides 36 of the hollow supporting arm 22 and is fixed at its proximal end to one end of a horizontally extending shaft 117. The other end of the shaft is journaled in a bearing 118 and has a segmental rack 119 keyed or otherwise fixedly secured thereto. The bearing 118 (see Figure 6) extends between the band type bracket 109 and the side 36 which is nearer the crank 116. The rack 119 (see Figure 12) meshes with stud-formed teeth 120 on one side of the plunger 25. The distal end of the crank 116 embodies a knob 121 for gripping purposes. When the crank 116 is swung downwards, as indicated by the arrow in Figure 13 of the drawings, the rack 119 swings downwards and operates through the medium of the teeth 120 to slide downwards the plunger 25. When the crank 116 is swung upwards the rack and teeth operate to retract the plunger. When it is desired to print with the apparatus the operator shifts the type case 24 until the desired or predetermined type is disposed beneath the plunger 25. Thereafter the crank 116 is swung downwards so as to cause the plunger 25 to slide downwards, enter the subjacent hole 100 and force downwards the aforementioned type. During downward movement of such type the enlarged head with the type character thereon moves towards the platen-forming strip 33 and when brought into engagement with the card makes an impression. Upon the retractile stroke of the crank the projected type moves upwards in response to the action of its compression spring and the plunger is slid upwards into its inoperative position. To form another letter it is only necessary properly to shift the type case and then by swinging downwards the crank 116 project the selected type and cause it to make the desired impression.

The card retaining bar 26 rests on and extends transversely across the top 27 of the base 21. It is disposed in parallel relation with the front 28 of the base and consists of a flat metal strip 122 and an upstanding rib 123. As hereinafter described, the bar is shiftable laterally, that is, to and from the front of the base for line spacing purposes and is also longitudinally shiftable for card shifting purposes. The strip 122 is slightly longer than the base 21 is wide and embodies a longitudinal series of card retaining spring type clips 124. These clips are applied to the rear margin of the strip 122 and are adapted, as shown in Figures 1 and 4, to grip the front margin of the card to be printed and hold it in clamped relation with the rear portion of the strip 122. When

the front margin of the card to be printed is inserted between the strip 122 and the clips the card is held in substantially fixed relation with the bar 26 and is movable or shiftable with the latter. The clips 124 have upturned rear or distal ends in order to permit of the ready entry of the front margin of the card to be printed between the clips and the subjacent or rear portion of the strip 122. The rib 123 extends across and is suitably secured to the central portion of the strip 122. It extends from one end of the strip 122 to the other and has a cut-out 125 in the central portion thereof (see Figures 17 and 18). The card retaining bar 26 is carried for transverse and longitudinal sliding movement by an elongated 15 guide member 126. This member is located directly in front of the bar 26 and extends transversely across the top 27 of the base 21. It is the same in length as the base is in width and consists of a flat metallic bottom strip 127, a top 20 channel strip 128, and a pair of rod type filler strips 129. The bottom strip 127 of the guide member underlies the strip 122 of the card retaining bar 26. It is approximately one-half again as wide as the strip 122, as shown in Figure 25 4, and is arranged so that its rear edge is flush with the rear end of the strip 122 and its front marginal edge projects forwards of the front edge of said strip 122. The channel strip 128 is suitably secured to the bottom strip 127 and is arranged so that one front flange rests on the strip 127 and its rear flange is in hooked relation with the rib 123. The filler strips 129 are located within the end portions of the channel strip 128 and fit between the front flange of the channel strip 35 and the front edge strip 122 of the card retaining bar 26. As the result of the arrangement of the three aforementioned strips of the guide member 126 and because of their respective positions relatively to the strip 122 and the rib 123 the card 40 retaining bar 26 is so connected to the guide member 126 that it is longitudinally shiftable with respect to the guide member and is conjointly movable with said member to and from the front of the base 21. When the card retaining bar 26 45 is shifted transversely as a result of forward or rearward shift of the guide member 126 the card to be printed, that is, the card which is retained by the clips 124 of the bar 26 against the strip 122 is shifted forwards or rearwards over the top 50 of the base. When the bar 26 is slid lengthwise the card is moved conjointly therewith in a side-wise direction.

Transverse shift of the card retaining bar 26 serves to move the card to be printed for line 55 spacing purposes. The mechanism for so shifting the bar 26 comprises a cross-shaft 130, a pair of pinions 131, and a pair of angle type rack-bars 132. The cross-shaft 130 is disposed beneath the central portion of the top 27 of the 60 base 21, as shown in Figure 6, and has one end thereof journaled in a bearing 133 on one of the sides 30 of the base 21. The other end of the shaft 130 projects through a circular hole 134 in the other side of the base and is provided on 65 the extremity thereof with a knurled shaft turning wheel 135. The latter is pinned or otherwise fixedly secured in place so that it operates when turned to rotate the shaft. The pinions 131 are fixed to the end portions of the shaft 130. They 70 are disposed slightly inwards of the sides 30 of the base of the apparatus and mesh with the rack bars 132. The rack bars (see Figures 4 and 6) are disposed inwardly of, and extend parallel to the base sides 30 and comprise hori- 75

horizontal legs 136 and vertical legs 137. The horizontal legs of the rack bars fit flatly against the under or bottom face of the top 27 of the base 21 and underlie slots 138 in the base top. The 5 vertical legs 127 are formed integrally with and depend from the outer margins of the horizontal legs and embody rack teeth 139 along their bottom margin. The slots 138 extend forwardly from the central portion of the top of the base 21 10 to the front margin of the base top and are of uniform width throughout their entire length. The front ends of the rack bars are provided with short slide pieces 140, and are secured to the ends of the guide member 126 by way of 15 screws 141. The slide pieces fit slidably in the slots 138 and are slightly longer than the bottom strip 127 of the guide member 26 is in width. The screws 141 extend upwards through the horizontal legs 136 of the rack bars 132 and project 20 through the slide pieces 140 into internally threaded sockets in the end portions of the bottom strip 127 of the guide member 126. The rear ends of the rack bars are slidably mounted in U-shaped guide members 142 which are 25 secured against the bottom face of the top 27 of the base 21. When the knurled wheel 135 is rotated in a counter-clockwise manner, as viewed in Figure 1, the pinions 131 are so rotated that they shift the rack bars 132 rearwards and cause 30 the latter to shift the guide member 126 and the card retaining bar 26 towards the rear portion of the base 21 of the apparatus. When the knurled wheel 135 is turned in the reverse direction, that is, in a clockwise manner as viewed in 35 Figure 1, the pinions 131 rotate in a reverse direction and cause the rack bars together with the guide member 126 and the card retaining bar 26 to move towards the front of the base 21. From the foregoing it is manifest that by turning 40 the knob in one direction or the other the card to be printed may be shifted to and from the front of the base and thus brought into the proper or desired position for printing. After a line of printing has been formed or made on the card, the card by operation of the aforementioned mechanism comprising the shaft 130, the pinions 131, and the rack bars 132 may be shifted rearwards in order to bring another portion of the card into position for printing. In order to 45 permit of accurate spacing of the lines of printing, a scale 143 is impressed or marked on the upper face of the top 27 of the base. This scale extends parallel to the sides of the base, as shown in Figures 1 and 14, and consists of a 50 longitudinal series of equidistantly spaced lines and numerical markings for certain of the lines. In order to prevent ready transverse shifting of the card retaining bar 26 a compression spring 55 144 is mounted on the end of the shaft which carries the knurled wheel 135. This spring abuts against the adjacent side 30 of the base 21 of the apparatus and the opposite pinion 131 and operates to exert such an axial pressure or thrust on the shaft 130 that the knurled wheel 135 is 60 caused frictionally to engage the adjoining side of the base 21. As a result of the action of the spring 144 there is a drag or brake action as far as the cross-shaft 130 is concerned and the card retaining bar 26 can hence not be shifted 65 transversely for line spacing purposes without the application of a comparatively strong turning force to the knurled knob 135. The central portion of the cross-shaft 130 extends through aligned holes 145 in the sides of the channel type 70 member 33, as shown in Figure 6.

The card to be printed is adapted after each impression, that is, each printing operation, to be shifted sidewise. Such shift of the card is effected by sliding the card retaining bar 26 longitudinally relatively to the guide member 126. 5 As hereinbefore pointed out, the apparatus includes mechanism for automatically sliding the bar 26 longitudinally for card feeding purposes, after each printing operation. This mechanism is actuated conjointly with the type projecting plunger 25, effects a step by step feeding of the card in response to successive impressions on the card, that is, printing operations, and comprises a vertically slideable control element 146. This element is positioned in side by side relation with the plunger 25 and is in the form of a plate metal stamping. It is substantially the same in length as the plunger and extends through and is slidably mounted in vertically aligned slots 147 in the plates 107 and 108. The slots 147 extend parallel to the sides of the base 21 and hence maintain the control element in a position wherein the sides thereof are parallel to the sides of the base and also the sides 36 of the hollow supporting arm 22. The lower end of the control element embodies a wedge formation 148 and the upper element projects upwards through the hole 115 in the top 37 of the supporting arm. The control element is connected to the type projecting plunger 26 by way of a tension spring 149 and a pin and slot connection 150. The spring 149 (see Figure 6) is disposed in front of and extends longitudinally of the plunger. The lower end of the spring is connected by a forwardly extending pin 151 to the plunger and the upper 35 end of the spring is connected by a laterally extending pin 152 to the control element 146. The control element is subjected to downward spring pressure and hence caused to move downwards when the plunger 25 is slid downwards by manipulation of the crank 116 for type projecting purposes. The pin and slot connection 150 consists of a vertically extending slot 153 in the central portion of the control element 146 and a laterally extending pin 154 on the plunger 25. 45 The pin 154 is normally disposed in the upper end of the slot 153 and operates when the plunger is shifted upwards to raise the control element. The pin and slot connection 150 between the plunger and the control element 146 50 permits the plunger to move downwards beneath the control element after the latter is arrested by abutment with the combined type selecting and positioning top plate 11 of the type case. When the plunger and control element are 55 shifted downwards from their fully retracted position, they move conjointly during the initial downward swing of the crank 116 and until the wedge formation 148 in the lower end of the control element engages or abuts against the plate 11. 60 During further downward swing of the crank 116 the plunger 25 moves downwards independently of the control member and projects downwards with the subjacent type (see Figure 13). This independent downward movement of the 65 plunger is permitted by the pin and slot connection 150 and results in an elongation of the tension spring 149. When the crank 116 is swung upwards to raise the plunger after a printing operation the plunger moves upwards independently of the control element 146 until the pin 154 of the pin and slot connection 150 engages the upper end of the slot 153. Thereafter the control element is caused positively to move upwards in unison or conjointly with the plunger. 70 75

The spring 149 and the pin and slot connection 150 constitute means whereby the plunger and control element are connected together so that during downward movement of the crank 116 5 they move downwards together until the element is arrested by the plate 77 and thereafter the plunger moves downwards independently of the element and in response to upward swing of the crank the plunger is shifted upwards independently of the control element during the initial 10 portion of the upward swing of the crank and thereafter the plunger and element are shifted upwards conjointly. In addition to the control element 146 the mechanism for automatically 15 sliding the card receiving bar 26 after each printing operation for card feeding purposes comprises a pair of lever forming arms 155 and 156, a link 157, a crank arm 158, a rock shaft 159, a crank 160, and a one-way clutch 161. The arm 20 155 is mounted on and extends forwardly and rearwardly from a pivot forming stud 162. The latter, as shown in Figure 4, is located in the central portion of the hollow supporting arm 22 and extends between and is secured to the 25 sides 36 of said arm. The front end of the arm 155 terminates adjacent to the front plate 38 of said hollow supporting arm and is connected to the control element 146 by a pin and slot connection 163. This connection comprises a laterally extending pin 164 on the element 146 and a horizontally extending slot 165 in the arm 155 and operates to cause the arm 155 to swing upwards and downwards in response to upward and downward shift of the control element. The rear end of 30 the lever arm 155 projects but a slight distance beyond the stud 162 and embodies a pair of vertically spaced inwardly extending lugs 166. The lever forming arm 156 is loosely mounted on the pivot forming stud 162 and extends rearwardly through the rear portion of the hollow supporting arm 22. It extends between the lugs 166, as shown in Figure 4, and through the medium of the latter is swung downwards in response to upward swing of the arm 155 and upwards in response to downward swing of said 35 last mentioned arm. The two arms 155 and 156 constitute a lever of the so-called "first" kind or type. The link 157 extends vertically and is disposed between the legs 35 for supporting the arm 22 in an elevated or overhanging position with respect to the base 21 of the printing apparatus. The upper end of the link projects into the rear portion of the compartment 40 in the arm 22 and is pivotally connected to the rear or distal end of the lever forming arm 156. The lower end of the link 157 projects through a hole 167 in the rear central portion of the top 27 of the base 21 and is pivotally connected to one end of the crank 158. The other end of 40 the crank 158 is in the form of a hub 168 which is mounted on and is fixed to the rear end of the rock shaft 159. The latter is disposed in and extends longitudinally of the channel type member 33 and is journaled in suitable bearings 45 at the ends thereof. The bearing for the front end of the rock shaft is fixed to the front 28 of the base 21, as shown in Figure 4. The rock shaft is square in cross-section and through the medium of the lever forming arms 155 and 156 and the links 157 and the crank 158 is rocked in 50 response to shift of the control member 146. The crank 160 projects upwards from the front end of the rock shaft and is connected to the clutch 161 by a pin and slot connection 169. The inner or lower end of the crank has an en- 55 larged hub 170 with a square opening 171 there- 60 in through which the front end of the rock shaft extends. By reason of the fact that this opening is square the crank is free to slide longitudinally of the rock shaft and at the same time is connected to the shaft so as to swing or rock therewith. The clutch 161 comprises a clutch dog 172, and a two piece housing for the dog. The housing consists of an inner stamped metal piece 173 and an outer stamped metal piece 174 and is 65 positioned above the rock shaft 159. The two housing pieces are suitably secured together in lapped relation and have vertically extending wedge-shaped notches 175 therein in which the clutch dog fits. The upper portion of the clutch 15 housing fits in a slot 176 in the central portion of the front margin of the bottom strip 127 of the guide member 126 and is carried or suspended for longitudinal sliding movement on the front margin of the strip 122 of the card retaining bar 20 26 by means of a pair of upper ears 177 and a pair of lower ears 178. The upper ears are formed integrally with and extend inwardly or rearwardly from the upper margin of the outer piece 174 of the clutch housing and fit against and rest on the top face of the front margin of the strip 122. The lower ears 178 are spaced beneath the upper ears and are formed integrally with the upper margin of the inner piece 173 of the clutch housing. They project inwardly from the housing piece 173 and fit against the bottom face of the front margin of the strip 122. The ears 177 and 30 178 constitute a connection whereby the clutch housing is suspended from the card retaining bar 26 and is connected to the latter so that it is 35 free to slide longitudinally thereof. The pin and slot connection 169 between the crank 160 and the clutch consists of a horizontally extending pin 179 on the upper or distal end of the crank and a vertically extending pin receiving slot 180 40 in the housing of the clutch. This pin and slot connection so connects the crank and the clutch housing that the clutch as a whole is shifted horizontally back and forth in the direction of the side base 21 in response to rocking of the 45 rock shaft 159. The crank 158 is so arranged that is operates to rock the rock shaft 159 in a clockwise manner when the control element 146 is slid or moved downwards with the plunger and in a counter-clockwise direction when the element is moved upwards with the plunger at the conclusion of a printing operation. As a result of this the clutch is shifted to the right during downward movement of the control element and is shifted to the left when the control element is raised. The clutch dog 172 is 50 positioned in an upstanding manner in the wedge-shaped notches 175 in the housing pieces and has a bifurcated lower end 181 which straddles the portions of the housing pieces which define the lower or pointed ends of the notches 175. The central portion of the clutch dog embodies a horizontally extending notch 182 through which the front margin of the strip 122 extends. The right hand portions of the wedge-shaped notches 175 55 are inclined or angled to the right and the left hand portions of the notches extend vertically. As a result of this notch design or arrangement the clutch dog is free to swing from a substantially vertical position wherein it is in unclutched relation with the front margin of the strip 122 into a tilted position wherein it is in clutched relation with said front margin of the strip 122 as the result of the gripping action of the edges 60 of the notch 182 on the strip 122. A U-shaped 65 70 75

spring 183 is attached to a forwardly extending lug 184 on the outer piece 174 of the clutch housing and operates to urge the clutch dog into its clutched position. When the clutch dog is in its clutched position, that is, in clutched relation with the front margin of the strip 122 of the card retaining bar 26 and the clutch is shifted to the left the bar 26 together with the card which is attached thereto is slid or fed lengthwise to the left. When the clutch is shifted to the right the clutch dog swings upwards into its unclutched position and releases the strip 122 of the card retaining bar 26 with the result that the clutch slides relatively to the bar and does not displace the latter. The card retaining bar 126 together with the card which is retained thereby is shifted to the left on the upstroke of the control element 146 and to the right on the down-stroke of said element. As a result of the action and arrangement and design of the clutch 161 the card retaining bar 26 is shifted to the left for card feeding purposes on the upstroke of the control element 146. During downward shift of said element the clutch slides to the right into a retracted position wherein it is again operative to shift the bar for card feeding purposes upon the next upward stroke of the control element 146. From the foregoing it is manifest that when the crank 116 is swung downwards in connection with a printing operation the clutch is slid to the right without moving or disturbing the card retaining bar 26. When the crank 116 is raised at the conclusion of the printing operation and the type projecting plunger 25 and the control member 146 are hence raised the clutch is shifted to the left and as a result of being in clutched relation with the strip 122 moves or feeds the bar 26 together with the card to the left. The upper end of the clutch dog 172 of the clutch extends upwards through a longitudinal slot 185 in the central or web portion of the top channel piece 128 of the guide member 126 and forms a handle whereby the dog may be manually shifted into its unclutched position when it is desired to free the card retaining bar 26 so that it together with the card may be shifted to the right for card adjusting or positioning purposes. The sides of the upper or handle forming ends of the clutch dog engage the sides of the slot 185 and hence the clutch 161 is connected to the guide member 126 so that it is shiftable bodily to and from the front of the base 21 with the guide member and card retaining bar. In order to cause the crank 159 to move with the clutch 160 when the guide member 126 and bar 26 are shifted to and from the front 28 of the base by manipulation of the knurled wheel 135 in connection with adjustment of the card to be printed, a bracket 186 is provided. This bracket is fixed to the bottom face of the bottom strip 127 of the guide member 126, extends downwards around the rock shaft 167 and is provided at its lower end with an upstanding fork 187 which fits within an annular groove 188 in the central portion of the hub 170 of the crank 160. Because of the construction of this bracket the crank 160 is caused to slide on the rock shaft 159 and maintain its operative relation with the clutch when the guide member and card retaining bar are shifted, as hereinbefore pointed out. A slot 189 in the central portion of the top of the base 21 permits the clutch 161 to move to and from the front of the base in connection with transverse adjustment of the guide member and card re-

taining bar. This slot 189, as shown in Figures 1 and 14, is of uniform width from end to end and extends rearwards from the front of the base 21 to the platen forming piece 32 where it joins or communicates with the square cut-out 31. In order to prevent any tendency of the card retaining bar 26 to follow the clutch 161 upon the retractile stroke of the latter and also to prevent over-feed or slide of the bar in the event that the feed stroke of the clutch is sudden or fast a leaf spring 190 and a shoe 191 are provided. The shoe, as shown in Figure 17, serves as a spring retainer and is mounted in the cut-out 125 in the central portion of the rib 123. The spring is riveted at the central portion thereof to the central portion of the shoe and is bowed so that the ends thereof bear downwards against the top face of the strip 122 of the card retaining bar 26. As the result of such bowing of the spring the shoe is urged upwards into frictional contact or engagement with the under-face of the web portion of the top channel piece 128 of the guide member 126 and hence produces a drag action which resists longitudinal sliding movement of the card retaining bar with respect to the guide member 126. An L-shaped bracket 192 is secured to one end of the strip 122. This bracket forms a finger piece whereby the card retaining bar 26 may be gripped in connection with manual sliding thereof relatively to the guide member 126.

The length or amount of feed of the card retaining bar 26 in response to the action of the one-way clutch at the conclusion of each printing operation depends upon the length of the stroke of the control element 146. When the up stroke of the control element is a long one the feed stroke of the card retaining bar is a long one. When the upstroke of the control element is short the feed stroke of the bar 26 is correspondingly short. In order adjustably to regulate or control the length of the stroke of the control element 146 so that such stroke is in proportion to the varying type widths slots 193 are formed in the combined type selecting and positioning top plate 77 of the type case 24. These slots are adapted to receive the wedge-formation 148 at the lower end of the control element 146, as shown in Figure 13, and extend at right angles to the front 75 of the case. They correspond in number to the square plunger-receiving holes 100 in the plates 77 and are associated with and located at one side of the holes 100 respectively. As shown in Figure 6 of the drawings, the spacing between the slots 193 and their respective holes 100 is the same as the spacing between the control element 146 and the type projecting plunger 25. When the type case is positioned so that one of the holes 100 is disposed beneath the plunger 25 and the crank 116 is swung downwards to effect a printing operation the plunger moves downwards through such hole as hereinbefore pointed out, and the control element moves downwards until the wedge formation 148 at its lower end enters and is stopped by the slot 193 which is associated with such hole 100. Each slot 193 is proportionately equal in width to the type character of the type with which it is associated with the result that the slots which are associated with comparatively wide type characters such as those forming the letters "W" and "M" are comparatively long and the slots which are associated with the small type characters such as those forming the letters "I" and "L" are comparatively short. When the control element 146 is shifted

downwards into a long slot 193 it travels further than when it is shifted downwards into a short slot and as a result it has a greater upward stroke and the card retaining element 26 together with the card is fed laterally a greater distance. By forming the slots 193 so that the length thereof is in proportion to the type with which they are associated lateral feed of the card retaining bar is controlled so that during normal or regular operation of the apparatus the impressions are spaced properly or equidistantly apart. As shown in Figures 1, 12, and 13, an elongated horizontally extending stop 194 is mounted on the side of the hollow supporting arm 15 against which the crank 116 is located. This stop limits upward swing of the crank 116 and is connected in place by screws 195 which pass through longitudinal slots 196 in the stop and permit the latter to be shifted or adjusted horizontally. By shifting or adjusting the stop the length of the upstroke of the control element 146 may be varied so as either to increase or decrease the spacing between the impressions which are formed during successive printing operations. By shifting the stop 194 forwards upward swing of the crank 16 is limited or restricted with the result that there is a corresponding diminution of the upstroke of the control element 146 which in turn results in a decrease in the spacing between successive impressions. By shifting or adjusting the stop rearwards so that it permits of greater upward swing of the crank 116 the upstroke of the control element 146 is increased with the result that greater spacing of the impressions is obtained. Adjustment of the stop is effected merely by loosening the screws 195 and shifting the stop either forwards or rearwards depending upon whether it is desired to lessen or increase the spacing.

As shown in Figure 4, the lugs 166 at the rear end of the lever forming arm 155 are spaced apart a distance slightly greater than the height of the portion of the lever forming arm 156 which is disposed therebetween. As a result of this, there is a lost motion connection between the arms 155 and 156. This connection is such that during the initial portion of the upstroke of the control element 146 the arm 155 imparts no downward motion to the arm 156 and hence there is no feed of the card retaining bar 26. As the result of the latter if it is necessary slightly to retract the type projecting plunger 25 because of failure properly to align the subjacent hole 100 therebeneath no motion is transmitted from the control element 146 to the arm 155 and hence there is no undesired or improper feed of the bar 26 with the card to be printed. The lugs 166 constitute a lost motion connection between the control element 146 and the clutch 161 whereby no feed movement is imparted to the clutch during the initial portion of the up or retractile stroke of said control element. In order to retain the lever forming arm 156 in the various positions into which it is swung by its counterpart, that is, the arm 155, two brake-type shoes 197 are provided. These shoes are positioned in opposed relation and abut against the central portions of the sides of the lever forming arm 156, as shown in Figures 4 and 6. They are urged inwards into frictional engagement with said arm 156 by way of compression springs 198. The latter are mounted on studs 199 which project inwards from the sides 36 of the hollow supporting arm 22. The arm 156 swings vertically between the two shoes and is not only held by the latter in its various

shifted positions but also is prevented from overswinging, that is, swinging to a greater extent than contemplated in the event of a sharp or quick swinging movement of the arm 155.

In addition to the various parts and members heretofore recited, the apparatus includes a gauge 200 for showing the operator of the apparatus the line on which impressions will be made by the type on the card to be printed and also comprises a latch 201 for locking the type case and carriage against sidewise shift when the apparatus is inoperative, as for example when it is being shipped or moved from place to place. The gauge fits slidably against the front end of the left hand side piece 46 of the carriage 23 and is confined to vertical sliding movement by means of a screw and slot connection 202. The lower end of the gauge is bent inwardly to form a horizontally extending card engaging part 203. This part embodies a gauge line or calibration 204, which when the gauge is shifted downwards marks on the subjacent card the impression line of the apparatus. The upper end of the gauge is bent outwards and forms a finger-piece 205 by which the gauge may be shifted downwards into its gauging or operative position. The gauge is urged upwards into an inoperative position wherein the member 200 is elevated with respect to the subjacent card, by means of a tension spring 206. The latter extends vertically and is connected at its lower end to a pin 207 on the central portion of the gauge and at its upper end to a laterally extending pin 208 on the contiguous side piece 46 of the carriage. The latch 198 is positioned in an upstanding manner against the right hand side piece 46 of the carriage 23 and is pivotally connected at its lower end by a screw 209 so that it may be swung from a substantially vertical position wherein it is inoperative forwards into a tilted position wherein it coacts with one end of the track 57 to hold the case and carriage against lateral or sidewise shift. Swinging movement of the latch is limited by way of a screw 210 which extends through an arcuate slot 211 in the central portion of the latch. When it is desired to lock the type case against sidewise shift the case together with the carriage is shifted to the right as far as possible in order to bring the latch 198 into alignment with the right hand end of the track 57. Thereafter the latch is shifted forwards into its operative position wherein it abuts against the right hand end of the track and thus locks the type case and carriage against sidewise shift to the left.

The operation of the printing apparatus is as follows: When it is desired to print a card to form it into a sign or placard for advertising or other purposes, the card is first placed on the top 27 of the base 21 of the apparatus and is then shifted or manipulated so as to bring the front margin thereof between the clips 124 and the strip 122 of the card retaining bar 26. After such manipulation the card is fixedly secured to the bar. After connection or attachment to the bar, as hereinbefore described, the card is shifted into the desired printing position beneath the plunger 25. If longitudinal adjustment of the card is desired, that is, adjustment to or from the front 28 of the base, the knurled wheel 135 is turned. If lateral adjustment of the card is necessary or desired the clutch 161 is first released by swinging the clutch dog 172 into its vertical or inoperative position and the card retaining bar 26 is shifted longitudinally in the desired direction. After properly adjusting the

card, the type case 24 is shifted by manipulation of the handle 90 to bring the desired type beneath the type projecting plunger 25. Thereafter the knob 121 is grasped by the operator and the crank 116 is swung forwards and downwards. This action of the crank causes downward movement of the plunger 25. During the initial portion of the plunger's downward movement the control element 146 moves downwards until the wedge formation 148 at its lower end enters and is stopped by the slot 153 at the side of the hole 100 which is directly beneath the plunger. During downward movement of the control element 146 the arm 155 swings the arm 156 upwards and causes the rock shaft 159 through the medium of the link 157 and the crank 158 to rock in such manner that the clutch 161 is shifted into its retracted position. During the latter portion of the downward stroke of the plunger 25 the type beneath the plunger is projected downwards and the type character on its enlarged head 92 is brought into engagement with the card and effects an impression. At the conclusion of this printing step the crank 116 is swung upwards into abutting relation with the stop 194. During the first or initial part of the upstroke of the crank the plunger 25 moves upwards independently of the control member 146. During such movement of the plunger the spring which is associated with the projected type moves the type upwards into its inoperative or normal position. During the end part or portion of the upward stroke of the plunger 25 the pin of the pin and slot connection 150 is brought into engagement with the upper end of the slot 153 and the control element 146 is thus connected to the plunger so that it is raised or shifted upwards with the latter. After take-up of the lost motion connection between the lever forming arms 155 and 156 the upstroke of the control member operates through the medium of the two lever-forming arms of the link 157, the crank 158, the rock shaft 159, crank 160, and the clutch 161 to shift the clutch in such direction that feeding of the card retaining bar together with the card is effected. After completion of the printing operation the type case is again shifted so as to bring the next desired type into position beneath the plunger 25. Thereafter the crank 116 is swung downwards and then upwards with the result that the desired impression is made on the card and the card is then fed laterally as hereinbefore described. During backwards and forwards shift of the type case the type characters 95 on the enlarged heads 92 of the type are brought into contact with the inking rolls 102 and are inked by the latter. After completion of a line of impressions on the card the card may if desired be shifted either to or from the front of the base 21 and another line of impressions made.

The herein described printing apparatus due to the specific arrangement of the parts thereof occupies but a small amount of space. It is extremely efficient in operation and may be manufactured at a comparatively low and reasonable cost.

The invention is not to be understood as restricted to the details set forth, since these may be modified within the scope of the appended claims, without departing from the spirit and scope of the invention.

Having thus described the invention, what I claim as new and desire to secure by Letters Patent is:

75 1. A printing apparatus comprising in combi-

nation a card supporting base, a forwardly extending arm overhanging the rear portion of the base, a carriage beneath the arm comprising a back piece and a pair of laterally spaced forwardly extending pieces and suspended from the front portion of the arm so that it is shiftable in a sidewise manner over the card, a type case with a set of individually and vertically movable type therein disposed within the carriage and connected to said side pieces so that it is shiftable sidewise with the carriage and is also shiftable relatively thereto to and from the front of the base, and a vertically slideable plunger carried by the front end of the arm over the type case and adapted when the case is shifted so that a type is disposed directly therebeneath to be lowered so as to shift the type and cause it to effect an impression on the card.

2. A printing apparatus comprising in combination a card supporting base, a forwardly extending arm overhanging the rear portion of the base, a U-shaped carriage beneath the front portion of the arm comprising a back piece and a pair of laterally spaced forwardly extending side pieces and suspended from said front portion of the arm so that it is shiftable in a sidewise manner over the card, a type case with a set of individually and vertically movable type therein disposed between the side pieces of the carriage and connected to the latter by roller and track connections so that it is shiftable sidewise with the carriage and is also shiftable relatively thereto to and from the front of the base, and a vertically slideable plunger carried by the front end of the arm over the type case and adapted when the case is shifted so that a type is disposed directly therebeneath to be lowered so as to shift the type and cause it to effect an impression on the card.

3. A printing apparatus comprising in combination a card supporting base, a forwardly extending hollow arm overhanging the rear portion of the base, a carriage disposed beneath the front portion of the arm and comprising a back piece and a pair of laterally spaced forwardly extending side pieces with opposed tracks on the inner faces thereof, means between the upper portion of the carriage and said front portion of the arm for suspending the carriage so that it is shiftable sidewise, a type case with a set of individually and vertically movable type therein disposed within the carriage and having rollers at the sides thereof engaging said tracks and forming connections between the type case and said side pieces of the carriage whereby the type case is shiftable sidewise with the carriage and is shiftable relatively thereto to and from the front of the base, and a vertically slideable plunger extending through the front end of the arm and over the type case and adapted when the case is shifted so that a type is disposed directly therebeneath to be lowered so as to shift the type and cause it to effect an impression on the card.

4. A printing apparatus comprising in combination a card supporting base, a forwardly extending hollow arm overhanging the rear portion of the base and having roller equipped brackets secured to and depending from the sides thereof, a U-shaped carriage disposed beneath the arm and comprising a back piece and a pair of laterally spaced forwardly extending side pieces, means including a runner extending across the top portion of the carriage and supported by the rollers for suspending the carriage from the arm so that it is shiftable in a sidewise manner over

the card, a type case with a set of individually and vertically movable type therein disposed between the side pieces of the carriage and connected to the latter so that it is shiftable sidewise with 5 the carriage and is also shiftable relatively thereto to and from the front of the base, and a vertically slideable plunger extending through the front end of the arm and over the type case and adapted when the case is shifted so that a type is 10 disposed directly therebeneath to be lowered so as to shift the type and cause it to effect an impression on the card.

5. A printing apparatus comprising in combination, a card supporting base, a forwardly extending hollow arm overhanging the rear portion of the base and brackets secured to and depending from the front portions of the side of the arm and having an upper and a lower roller mounted thereon, a U-shaped carriage disposed beneath the arm and comprising a back piece and a pair of laterally spaced forwardly extending side pieces, means for suspending the carriage from the arm so that it is shiftable in a sidewise manner over the card including a horizontal runner fitting between the upper and lower rollers and extending across and secured to the upper margin of the back piece of the carriage, a type case with a set of individually and vertically movable type therein disposed between the side 25 pieces of the carriage and connected to the latter so that it is shiftable sidewise with the carriage and is also shiftable relatively thereto to and from the front of the base, and a vertically slideable plunger extending through the front end of the arm and over the type case and adapted when the case is shifted so that a type is disposed directly therebeneath to be lowered so as to shift the type and cause it to effect an impression on the card.

40 6. A printing apparatus comprising in combination a card supporting base, a forwardly extending arm overhanging the rear portion of the base, a U-shaped carriage disposed beneath the front portion of the arm and comprising a back piece and a pair of laterally spaced forwardly extending side pieces, means for suspending the carriage from the arm so that it is shiftable sidewise over the card including an elongated horizontally extending track disposed beneath and secured to the front end of the arm and an elongated horizontally extending runner mounted on the track and extending across and secured to the upper central portions of the side pieces, a type case with a set of individually and vertically movable type therein disposed between the side pieces of the carriage and connected to the latter so that it is shiftable sidewise with the carriage and is also shiftable relatively thereto and from the front of the base, and a vertically slideable plunger carried by the front end of the arm in front of the track and adapted when the case is shifted so that a type is disposed directly therebeneath to be lowered so as to shift the type and cause it to effect an impression on the card.

65 7. A printing apparatus comprising in combination a card supporting base, a forwardly extending hollow arm overhanging the rear portion of the base, a U-shaped carriage disposed beneath the front portion of the arm and comprising a back-piece and a pair of laterally spaced forwardly extending side pieces, means for suspending the carriage so that it is shiftable sidewise over the card including an elongated horizontally disposed track extending under and secured to the front portions of the sides of the

arm, a coextensive horizontally disposed runner extending across and secured to the central portions of the side pieces of the carriage and arranged so that it overhangs said track, and balls between the track and runner, a type case with a set of individually and vertically movable type therein disposed between the side pieces of the carriage and connected to the latter so that it is shiftable sidewise with the carriage and is also shiftable relatively thereto to and from the front 10 of the base, and a vertically slideable plunger in front of the track extending through and mounted slidably in the front end of the arm and adapted when the case is shifted so that the type is disposed directly therebeneath to be lowered and 15 to shift the type so as to cause it to effect an impression on the card.

8. A printing apparatus comprising in combination a card supporting base, a forwardly extending arm overhanging the rear portion of the base, a U-shaped carriage beneath the arm suspended from the front portion of the arm so that it is shiftable sidewise over the card and comprising a back piece, a pair of laterally spaced side pieces extending forwardly from the ends 25 of the back piece and provided with horizontally extending angle bar type runners along the inner faces thereof, a type case with a set of individually and vertically movable type therein disposed within the carriage and having upper 30 and lower rollers at the sides thereof fitting at the top and beneath the tracks respectively and forming connections between said type case and said side pieces of the carriage whereby the type case is shiftable sidewise of the carriage and is 35 also shiftable relatively to the carriage to and from the front of the base, and a vertically slideable plunger carried by the front end of the arm over the type case and adapted when the case is shifted so that a type is disposed directly there- 40 beneath to be lowered so as to shift the type and cause it to effect an impression on the card.

9. A printing apparatus comprising in combination a card supporting base, a forwardly extending arm overhanging the rear portion of the base, a carriage disposed beneath the front portion of the arm and comprising a back piece and a pair of laterally spaced side pieces secured to and extending forwardly from the ends of the back piece and provided with opposed tracks on 45 the inner faces thereof, means between the upper portion of the carriage and said front portion of the arm for suspending the carriage so that it is shiftable sidewise over the card, a type case with a set of individually and vertically movable 50 type therein disposed within the carriage and having rollers at the sides thereof engaging said tracks and forming connections between the tracks and said side pieces of the carriage whereby the type case is shiftable sidewise with the carriage and is shiftable relatively thereto to and from the front of the base, a roll for inking the type carried by the carriage and extending between the side pieces of the latter and beneath the tracks, and a vertically slideable plunger carried by the front end of the arm over the type 55 case and adapted when the case is shifted so that a type is disposed directly therebeneath to be lowered so as to shift the type and cause it to effect an impression on the card.

70 10. A printing apparatus comprising in combination a card supporting base, a forwardly extending arm overhanging the rear portion of the base, a carriage disposed beneath the front portion of the arm comprising a back piece, a pair 75

- of laterally spaced forwardly extending side pieces, means for suspending the carriage so that it is shiftable sidewise over the card including an elongated horizontally disposed track extending under and secured to the front portion of the arm, a substantially coextensive horizontally disposed runner coacting with the track and secured to and extending across the upper central portions of the side pieces of the carriage, a type 5
 10 case with a set of individually and vertically movable type therein disposed between the side pieces of the carriage and connected to the latter by roller and track connections so that it is shiftable sidewise with the carriage and is also shiftable relatively thereto to and from the front of the base, means for locking the carriage and type case against sidewise shift when the apparatus is not in use consisting of a latch pivotally connected to one of the side pieces of the 15
 20 carriage and adapted to be brought into abutting relation with one end of the track of the suspension means, and a vertically slidable plunger carried by the front end of the arm over the type case and adapted when the case is shifted so that a type is disposed directly therebeneath to be lowered so as to shift the type and cause it to effect an impression on the card.
11. A printing apparatus comprising in combination a card supporting base, a forwardly extending arm overhanging the rear portion of the base, a U-shaped carriage beneath the front portion of the arm comprising a back piece and a pair of laterally spaced forwardly extending side pieces and suspended from said front portion of the arm so that it is shiftable in a sidewise manner over the card, a type case with a set of individually and vertically movable type therein disposed between the side pieces of the carriage and connected to the latter so that it is shiftable 30

ing the card for impression spacing purposes comprising a one way clutch applied to the bar and adapted when moved in one direction to move the bar and card and when moved in the opposite direction to release the bar and move into a retracted position, a control element associated with the plunger and connected to the latter so that it is moved back and forth thereby in response to vertical movement of the plunger, and an operating connection between the element and the clutch adapted to move the clutch back and forth in response to back and forth movement of the element and including a lost motion connection whereby movement of the clutch is precluded during the initial movement of the element by the plunger.

16. A printing apparatus comprising in combination a card supporting base, a longitudinally shiftable card retaining bar extending transversely across the base, an arm supported by the base so that it overhangs the latter, a type case provided with a set of individually and vertically movable type therein and mounted so that it is shiftable universally in a horizontal plane under the arm and over the card, a vertically slidable plunger carried by the arm and adapted when the case is shifted so that a type is disposed directly therebeneath to be lowered so as to shift the type and cause it to effect an impression on the card, and means for automatically feeding the card for impression spacing purposes comprising a one-way clutch applied to the bar and adapted when moved in one direction to move the bar and card and when moved in the opposite direction to slide relatively to the bar into a retracted position, a control element carried by the arm for vertical sliding movement connected to the plunger for vertical shift thereby, and a separate connection between the element and the clutch adapted to move the clutch back and forth in response to vertical shift of the element and including a lost motion connection whereby movement of the clutch is precluded during the initial part of either downward or upward shift of the element by the plunger.

17. A printing apparatus comprising in combination card supporting base, a longitudinally shiftable card retaining bar extending transversely across the base, an arm supported by the base so that it overhangs the latter, a type case provided with a set of individually and vertically movable type therein and mounted so that it is shiftable universally in a horizontal plane under the arm and over the card, a vertically slidable plunger carried by the arm and adapted when the case is shifted so that a type is disposed directly therebeneath to be lowered so as to shift the type and cause it to effect an impression on the card, automatic feed means for the card comprising a one-way clutch applied to the bar and adapted when moved in one direction to move the bar and card and when moved in the opposite direction to release the bar and move into a retracted position, a control element carried by the arm for vertical sliding movement and so connected to the plunger and controlled that it moves downwards with the plunger during the initial portion of downward shift of the plunger and moves upwards with the plunger during the latter part of upward movement of the latter, and an operating connection between the element and the clutch for moving the latter back and forth in response to vertical shift of the former.

18. A printing apparatus comprising in com-

bination a card supporting base, a longitudinally shiftable card retaining bar extending transversely across the base, an arm supported by the base so that it overhangs the latter, a type case provided with a set of individually and vertically movable type therein and mounted so that it is shiftable universally in a horizontal plane under the arm and over the card, a vertically slidable plunger carried by the arm and adapted when the case is shifted so that a type is disposed directly therebeneath to be lowered so as to shift the type and cause it to effect an impression on the card, and means for automatically feeding the card for impression spacing purposes comprising a one-way clutch applied to the bar and adapted when moved in one direction to move the bar and card and when moved in the opposite direction to slide relatively to the bar into a retracted position, a control element carried by the arm for vertical sliding movement connected to the plunger for vertical shift thereby, and an operating connection between the element and the clutch adapted to cause the clutch to move in said one direction during upward shift of the element and in said opposite direction in response to downward shift of the element and including a lost motion connection whereby movement of the clutch is precluded during the initial portion of the down and upstroke of the element.

19. A printing apparatus comprising in combination a card supporting base, a longitudinally shiftable card retaining bar extending transversely across the base, an arm supported by the base so that it overhangs the latter, a type case with a set of individually and vertically movable type therein mounted so that it is shiftable universally in a horizontal plane under the arm and over the card and provided at the top thereof with a type positioning and selecting plate having holes therein in alignment with the type and slots alongside of the holes, a vertically slidable plunger carried by the arm and adapted when the case is shifted so that a type is disposed directly therebeneath to be shifted downwards through the subjacent hole in the plate and to shift the type and cause it to effect an impression on the card, and means for automatically feeding the card for impression spacing purposes comprising a one way clutch adapted when moved in one direction to move the bar and card and when moved in the opposite direction to release the bar and move into a retracted position, a vertically slidable control element adjacent to the plunger provided at the lower end thereof with a wedge-shaped slot receiving formation and connected to the plunger so that when the latter is shifted downwards for type shifting purposes to be moved downwards until arrested as the result of engagement with the slot at the side of the hole that is beneath the plunger, and also so that when the plunger is shifted upwards it is also shifted upwards, and an operating connection between the element and the clutch for moving the latter back and forth in response to vertical shift of the former.

20. A printing apparatus comprising in combination a card supporting base, a longitudinally shiftable card retaining bar extending transversely across the base, an arm supported by the base so that it overhangs the latter, a type case with a set of individually and vertically movable type therein mounted so that it is shiftable universally in a horizontal plane under the arm and over the card and provided at the top thereof with a type positioning and selecting plate having holes

- therein in alignment with the type, a vertically slidable plunger carried by the arm and adapted when the case is shifted so that a type is disposed directly therebeneath to be shifted downwards through the subjacent hole in the plate and to shift the type and cause it to effect an impression on the card, and means for automatically feeding the card for impression spacing purposes comprising a one way clutch adapted when moved in one direction to move the bar and card and when moved in the opposite direction to release the bar and move into a retracted position, a vertically slidable control element adjacent to the plunger connected to the plunger by a spring so that it is downwardly shiftable with the plunger until arrested by contact with the plate and also connected to the plunger by way of a pin and slot connection so that it is retracted by the plunger during the latter portion of upward shift thereof, and an operating connection between the element and the clutch for moving the clutch back and forth in response to vertical shift of the element.
21. A printing apparatus comprising in combination a card supporting base, a longitudinally shiftable card retaining bar extending transversely across the base, an arm supported by the base so that it overhangs the latter, a type case with a set of individually and vertically movable type therein mounted so that it is shiftable universally in a horizontal plane under the arm and over the card and provided at the top thereof with a type positioning and selecting plate having holes therein in alignment with the type, a vertically slidable plunger carried by the arm and adapted when the case is shifted so that a type is disposed directly therebeneath to be shifted downwards through the subjacent hole in the plate and to shift the type and cause it to effect an impression on the card, and means for automatically feeding the card for impression spacing purposes comprising a one way clutch adapted when moved in one direction to move the bar and card and when moved in the opposite direction to release the bar and move into a retracted position, a vertically slidable control element adjacent to the plunger connected to the plunger by a spring so that it is downwardly shiftable with the plunger until arrested by contact with the plate and also connected to the plunger by way of a pin and slot connection so that it is retracted by the plunger during the latter portion of upward shift thereof, and an operating connection between the element and the clutch adapted to move the clutch in said one direction in response to upward shift of the element and to move the clutch in said opposite direction in response to downward movement of the plunger and including a lost motion connection whereby

no movement is imparted to the clutch during the initial portion of the up and down stroke of the element.

22. A printing apparatus comprising in combination a card supporting base, a hollow arm supported by the base so that it overhangs the latter, a type case provided with a set of individually and vertically movable type therein and mounted so that it is shiftable universally in a horizontal plane under the arm and over the card, a vertically slidable plunger extending through the arm and adapted when the case is shifted so that a type is disposed therebeneath to be lowered so as to shift the type and cause it to effect an impression on the card, means for shifting the plunger for type shifting purposes including a crank on the outside of the arm, automatic feed means for the card comprising a vertically slidable control element extending through the arm in close proximity to the plunger and connected to the latter so that it is shiftable downwards during the initial part of the downstroke of the plunger and is shifted upwards during the latter part of the upstroke of the plunger, and an adjustable stop for limiting swinging of the crank in the direction which effects upward shift of the plunger and the control element.

23. A printing apparatus comprising in combination a card supporting base, a longitudinally shiftable card retaining bar extending transversely across the base, an arm supported by the base so that it overhangs the latter, a type case provided with a set of individually and vertically movable type therein and mounted so that it is shiftable universally in a horizontal plane under the arm and over the card, a vertically slidable plunger carried by the arm and adapted when the case is shifted so that a type is disposed directly therebeneath to be lowered so as to shift the type and cause it to effect an impression on the card, automatic feed means for the card comprising a one-way clutch applied to the bar and adapted when moved in one direction to move the bar and card and when moved in the opposite direction to release the bar and move into a retracted position, a movable control element carried by the arm adjacent to the plunger and connected to the latter so that it is shiftable back and forth in response to vertical shift of the plunger and an operating connection between the element and the clutch for moving the clutch back and forth in response to back and forth movement of the element, and means whereby the clutch may be manually released with respect to the bar so that the latter may be shifted longitudinally in either direction in connection with manual adjustment of the card.

ROBERT J. THORN.
